Primary Examiner — Garth Rademaker*Assistant Examiner* — Katelin G Kloberg(74) *Attorney, Agent, or Firm* — Ware, Fressola, Maguire & Barber LLP**CLAIM**

I claim the ornamental design of a bearing frame, as shown and described.

DESCRIPTION

FIG. 1 is a top back perspective view of a bearing frame according to the present invention;

FIG. 2 is a bottom front perspective view thereof;

FIG. 3 is a side elevation view thereof;

FIG. 4 is an opposite side elevation view thereof;

FIG. 5 is a front view thereof;

FIG. 6 is a back view thereof;

FIG. 7 is a top view thereof; and,

FIG. 8 is a bottom view thereof.

The broken lines represent portions of the bearing frame and form no part of the claimed design.
